W. E. JUNE

SHELVING CONSTRUCTION

Filed Nov. 9, 1927

Inventor

WILLIAM E. JUNE

By

W. E. June

Attorney

UNITED STATES PATENT OFFICE.

WILLIAM E. JUNE, OF DENVER, COLORADO, ASSIGNOR TO PERRY E. JUNE, OF SACRAMENTO, CALIFORNIA.

SHELVING CONSTRUCTION.

Application filed November 8, 1927. Serial No. 232,034.

This invention relates to shelving construction, and has for its principal object, the provision of a series of members which can be quickly and easily assembled as a case of shelves, or disassembled without the use of tools.

Another object of the invention is to construct the various members so that each member will interlock with another member without the use of extraneous brackets, clamps, etc.

A further object of the invention is to provide shelving which can be added to or subtracted from without interfering with the remaining shelves, and without it being necessary to use nails, screws, bolts and the like.

Other objects and advantages reside in the detail construction of the invention, which is designed for simplicity, economy and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of a pair of cleats such as are employed for supporting the shelves from the stiles.

Fig. 2 is a plan view of a typical shelf.

Fig. 3 is a fragmentary perspective view of a portion of the stile employed in my improved shelving.

Fig. 4 is a perspective view of the interlocking plug employed for locking the cleats to the stiles and the shelves to each other and to the cleats.

Fig. 5 is a fragmentary perspective view illustrating the junction between the cleats and the stile.

Fig. 6 is a similar view illustrating the shelves in place on the cleats ready to receive the plug of Fig. 4.

Fig. 7 is a detail view of an alternate form of interlocking device which displaces the plug of Fig. 4.

The invention comprises a series of vertical stiles 10 of any convenient length. The stiles 10 are preferably wooden and T-shaped in cross section. Inset in the sides formed by the T-shaped cross section, are spacing strips 11, which may be held in place on the stiles

by means of suitable screws 12. The lower extremity of each of the spacing strips 11 is beveled or cut at an angle such as shown at 13, the upper extremity being at right angles to the length of the strip. This cutting of the strip extremities forms dove-tailed mortises 14 opposite each other on the stile 10 and at spaced intervals along its length corresponding to the space desired between the shelves.

To support the shelves on the stiles 10, cleats 15, such as illustrated in Fig. 1, are employed. The cleats 15 are always used in pairs. The extremities of each cleat carries a dove-tailed tenon 16 adapted to fit into the dove-tailed mortises 14 on the stiles. When the pair of cleats are in their mortises 14, they assume the position of Fig. 5, coming together throughout their length to form a single shelf supporting cleat. In the inner face of each cleat, a transverse dove-tailed groove 17 is formed which, when the cleats 15 are together, as in Fig. 5, form a double dove-tailed socket for the reception of a similarly shaped interlocking plug 23, illustrated in Fig. 4.

A typical shelf is illustrated at 18, Fig. 2, the corners of which are inset at 19 to fit around one-half of the stile 10 and the ends of which carry dove-tailed cuts 20. The shelves are placed upon the cleats 15 so that the cuts 20 register with and form a double dove-tailed opening over the similarly shaped socket in the cleats. The plugs 18 are then forced through the dove-tailed openings in the shelves and in the cleats.

The interlocking plugs 23 contain V-shaped grooves 24 and are slightly tapered. As they are forced into the dove-tailed openings, they act to simultaneously draw the two shelf ends together, lock the shelves to the cleats, and draw the two cleats of a pair together, causing the tenons 16 to snugly engage the mortises 14 in the stiles. By this construction, the entire case of shelves is tightly locked together but can be easily disassembled by simply removing the interlocking plugs 23 which release every member of the construction.

To avoid forming the dove-tailed grooves in the cleats and shelves, an interlocking member, such as illustrated in Fig. 7, may be used. This member consists of a U-shaped clip 21 carrying short dowel pins 22. The clip 21 is placed over the two co-acting cleats 15 so as

to maintain the tenons 16 in their mortises 14. The pins 22 project upwardly and are received in holes bored adjacent each extremity of each shelf in a position such as indicated 5 in broken line at 25, Fig. 2.

While a specific form of the improvement has been described and illustrated herein, it is desired to be understood that the same may be varied, within the scope of the appended 10 claims, without departing from the spirit of the invention.

Having thus described the invention, what I claim and desire secured by Letters Patent is:—

15. 1. Shelving construction comprising vertical stiles; dove-tailed recesses in the sides of said stiles; cleats having dove-tailed extremities adapted to fit within said recesses; shelves arranged to be carried by said cleats; 20 means for clamping a pair of cleats together, so that the extremities of the pair will engage in recesses on opposite sides of said stiles, said means adapted to also clamp adjoining shelves together.
25. 2. Shelving construction comprising vertical stiles; spacing strips attached to the sides of said stiles; the extremities of said strips being spaced apart and shaped to leave dove-tailed recesses; cleats; dove-tailed extremities 30 on said cleats adapted to fit into the said recesses and shelves arranged to be carried by said cleats.
35. 3. Shelving construction comprising vertical stiles; dove-tailed recesses in the sides of said stiles; cleats having dove-tailed extremities adapted to fit within said recesses; shelves arranged to be carried by said cleats; means for clamping a pair of cleats together, so that the extremities of the pair will engage 40 in recesses on opposite sides of said stiles, said means adapted to also clamp adjoining shelves together; dove-tailed grooves extending transversely of one face of said cleats and a double dove-tailed plug adapted to fit into 45 co-acting grooves so as to clamp two said

cleats together into opposite sides of said stiles.

4. Shelving construction comprising vertical stiles; dove-tailed recesses in the sides of said stiles; cleats having dove-tailed extremities adapted to fit within said recesses; shelves arranged to be carried by said cleats; means for clamping a pair of cleats together, so that the extremities of the pair will engage in recesses on opposite sides of said stiles, 50 said means adapted to also clamp adjoining shelves together; dove-tailed grooves extending transversely of one face of said cleats and a double dove-tailed plug adapted to fit into co-acting grooves so as to clamp two said 55 cleats together into opposite sides of said stiles, said plugs arranged to extend into dove-tailed cuts in the extremities of said shelves so as to lock adjoining shelves together.

5. Shelving construction comprising vertical stiles; opposite dove-tailed recesses in the sides of said stiles; cleats; dove-tailed projections on the extremities of said cleats, 60 said projections being flush with one side of said cleats and inset from the other side thereof, so that when said projections are in said recesses two cleats may come together; means for maintaining said cleats together, and shelves adapted to rest on said cleats.

6. Shelving construction comprising vertical stiles; opposite dove-tailed recesses in the sides of said stiles; cleats; dove-tailed projections on the extremities of said cleats, 70 said projections being flush with one side of said cleats and inset from the other side thereof, so that when said projections are in said recesses two cleats may come together; means for maintaining said cleats together; shelves adapted to rest on said cleats, said means for 75 maintaining two of said cleats together, also acting to maintain two of said shelves together.

In testimony whereof, I affix my signature.

WILLIAM E. JUNE.
